UNITED STATES PATENT OFFICE.

THOMAS SPILLANE, OF NEW BETHLEHEM, PENNSYLVANIA, AND THOMAS BRINNING,
OF MOUNT VERNON, OHIO.

APPARATUS FOR REMOVING GLASS.

1,156,379.

Specification of Letters Patent.

Patented Oct. 12, 1915.

Application filed June 11, 1914. Serial No. 844,400.

To all whom it may concern:

Be it known that we, THOMAS SPILLANE, of New Bethlehem, in the county of Clarion and State of Pennsylvania, and THOMAS BRINNING, of Mount Vernon, in the county of Knox and State of Ohio, have invented a certain new and useful Apparatus for Removing Glass, of which the following is a specification.

10 The invention relates to apparatus for removing glass from drawing rings or pots in the manufacture of window glass. After a cylinder has been drawn, either from a pot or a drawing ring in a tank, and has been 15 cut off, a residue of cold glass is left in the pot or ring, tending to interfere with subsequent drawings. It is customary to skim this old glass out by means of a hand tool, and it is the purpose of our invention to provide an improved apparatus for accomplishing 20 this result and for getting rid of all the cold glass in the ring or pot, so that in the case of a pot it need not be inverted to dump the glass, and in the case of a drawing ring 25 in a tank another draw can be taken without waiting a relatively long period for the glass in the ring to re-heat. One form of apparatus for carrying out the invention is 30 illustrated in the accompanying drawing, wherein—

Figure 1 is a side elevation of the apparatus, partially in section, and showing such apparatus in operative position with respect to the drawing ring from which the old 35 glass is to be removed, Fig. 2 is a plan view of the mechanism for driving the main shaft, and Fig. 3 is a section on the line III—III of Fig. 1.

In the drawing, 1 is a wheeled truck 40 which supports the apparatus; 2 is a tank containing a body of molten glass, and 3 is a drawing ring from which a glass cylinder has been drawn and from which it is 45 desired to remove the cold glass so as to prepare the ring for a new drawing operation.

The apparatus for taking the glass from the interior of the ring comprises a flat plate 4 arranged spirally upon the shaft 5, and a casing 6 which surrounds the spiral 4. The 50 casing 6 is provided with an upper sleeve portion 7 carrying at its upper end a bearing block 8, and the shaft 5 is provided with a bearing block 9 held against movement longitudinally of the shaft so that the 55 weight of the shaft 5 is supported by the

sleeve 7 and any upward movement of the sleeve is transmitted to the shaft.

The sleeve 7 which carries the casing 6 is mounted for vertical sliding movement through the part 10 of the framework carried by the truck 1, and is provided on one side with a rack 11 (Fig. 3). This rack 11 is engaged by a pinion 12 mounted on the shaft 13 and operated from the electric motor 14. It will thus be seen that means are 60 provided for moving the casing 6 vertically and that this movement necessarily causes the shaft 5 and the spiral 4 to move vertically with the casing.

The shaft 5 is guided at its upper end in 70 a bearing 15 carried by the upper portion 16 of the framework, and above this bearing is a worm wheel 17 for rotating the shaft 5 so that the shaft may move vertically therethrough, the worm wheel being operated 75 by the worm 18 carried by the shaft 19 and operated by the electric motor 20.

The truck 1 is provided with a turn-table mechanism comprising a pair of opposing bearing plates 21 and 22 and a vertical shaft 80 23, so that after the casing 6 and spiral 4 have been moved upward above the tank the entire apparatus can be rotated laterally around the shaft 23 as an axis, the motors 14 and 20 serving to counterbalance the 85 weight of the casing, spiral and operating parts.

In operating the apparatus the truck is brought to the position illustrated in Fig. 1 and the motor 14 is operated to lower casing 6 and spiral 4 so that the lower edges thereof are just below the surface of the glass in the ring 3. Motor 20 is then operated to rotate the shaft 5 which rotation of the shaft 5 causes the surface glass in the ring 3 to rise up on the surface of the spiral 4. The motor 14 is then operated to raise the casing 6 and spiral 4, the rotation of the latter being continued to prevent the glass from flowing back into the tank. After the casing and spiral have been raised 90 the apparatus is swung laterally around the shaft 23 as an axis and the rotation of the shaft 5 is stopped to permit the removal of the glass from the spiral. The semi-fluid glass can be scraped from the surface of the spiral, although in some cases the glass will be sufficiently fluid to run off the surface of the spiral with only a slight amount of assistance from a scraping tool. As here- 100 105 110

tofore indicated the device may be used for removing the glass from a pot as well as from a ring, the method of procedure being the same in both instances.

- 5 The method of cleaning the ring or pot is advantageous for the reason that the cold glass is thoroughly and quickly skimmed from the body of the glass in the ring or pot, and a minimum amount of time is lost
10 in preparing the receptacle for a new draw. The cold glass is removed cleanly from the receptacle, and no residue is left as in the case where hand skimming is attempted and wherein the workman is greatly hampered
15 by the heat in carrying out the skimming operation. Other advantages incident to the process and apparatus skimming operation will be readily apparent to those skilled in the art.
- 20 What we claim is:

1. A device for removing glass from a pot or drawing ring, comprising a vertical

spiral, a cylindrical casing surrounding the spiral, means for moving the spiral and casing vertically and laterally, and means for 25 rotating the spiral.

2. A device for removing glass from a pot or drawing ring, comprising a vertical spiral having its lower end formed into an inclined skimming plate, a cylindrical casing surrounding the spiral, means for moving the spiral vertically and laterally, and means for rotating the spiral.

In testimony whereof we have hereunto signed our names in the presence of the subscribed witnesses.

THOMAS SPILLANE.
